COUNTERBALANCING DEVICE

Richard R. Bloss and Roy C. Pfeil, Columbus, Ohio, assignors, by mesne assignments, to International-Stacey Corporation, Franklin, Ohio, a corporation of Ohio

Application April 6, 1928, Serial No. 268,028

10 Claims. (Cl. 74—591)

Our invention relates to a counterbalancing device and, more particularly, to a counterbalancing device that is attached to and operates in conjunction with the crank of an oil well drilling and pumping mechanism.

This application is a continuation in part of our application, Serial Number 228,963, filed October 26, 1927.

Certain features of adjustability have been provided in order to meet the normal variations in the weight of the suspended drilling and pumping mechanism and the oil or other fluid above the plunger. Also, features of adjustability have been provided whereby the counterbalance effect 10 may be synchronized with the reaction in the pitman that result from the sucker rod pull. These features of adjustability are calculated to make it possible to eliminate the jerky movements of the various parts of the drilling and pumping 15 mechanism and thereby provide a smooth and uniform operation throughout all cycles of such drilling and pumping.

The fact that our counterbalance is so designed as to be attached to and operate with the 20 crank has decided advantages over a band wheel or walking beam counterbalance. Some of these advantages reside in the fact that the wear and tear on the band wheel and walking beam and the torsional stress on the crank shaft, as produced by ordinary types of band wheel or walking 25 beam counterbalances, are eliminated. With our design and construction, we avoid unusual stress on any part of the drilling and pumping mechanism, with the exception of the crank arm 30 itself.

Other advantages of our device reside in the fact that our counterbalance, being so designed as to be attached to and operate with the crank, is located outside of the rig house whereby it may 35 be readily adjusted and operated. It is so constructed that it may be quickly and easily shifted in an arcuate path with relation to the crank arm to synchronize the counterbalance effect with the load.

In our invention, we have provided a plurality of weight members that may be attached to or 40 detached from the counterbalance. Such weights are provided so as to obtain a greater or lesser counterbalancing effect since, by varying the 45 number of weight members and thereby varying the mass of weight of the counterbalance, any desired counterbalancing effect may be obtained.

Also, we have provided means whereby the counterbalance may be detached from the crank 50 shaft on which it is mounted and such crank shaft

thereby relieved of the weight thereof. Further, we have provided a means for maintaining the counterbalance in such position with relation to the crank and crank shaft that it may be quickly and easily remounted on the crank shaft after 5 it has been detached therefrom.

Various other advantageous features will appear from the following detailed description and the preferred embodiment of our invention may be seen in the accompanying drawing wherein 10 similar characters of reference designate corresponding parts and wherein:

Figure 1 is a side view showing the application of our invention to an ordinary pumping and drilling rig structure.

Figure 2 is a side elevation of our counterbalancing device shown applied to the crank of an ordinary drilling and pumping mechanism. The counterbalancing device is shown in inoperative position by the dotted line.

Figure 3 is an end elevation of a part of an oil well drilling and pumping mechanism with our counterbalancing device attached thereto.

Referring to the drawing, particularly to Figure 1, we have shown the usual drilling rig structure comprising the engine house 1, belt house 2, band wheel house 3 and derrick structure 4. In this figure, we have shown a novel counterbalancing unit 5 as being disposed on the outside of the house 3 which encloses the band wheel 6. 30 A sand reel 7 is also disposed on the outside of the house 3.

As best shown in Figures 2 and 3, a crank arm 8 is mounted upon and keyed to a crank shaft 9 which, in turn, operates in a bearing 10 that 35 may be supported on a jack-post or similar structure 11.

The counterbalance unit 5 is preferably mounted on the hub of the crank arm 8 in a position between the crank arm 8 and the jack-post or similar supporting structure 11 by means of a semi-circular clamp 12 cooperating with a semi-circular recessed portion 13 in the counterbalance unit 5. Such counterbalance unit is provided with a plurality of tapered sockets 14 which are designed to cooperate with a tapered boss 15 mounted on a lug 16 that extends laterally from the crank 8. It will be understood that the tapered boss 15 may be attached to or form an integral part of the crank 8 and extend therefrom at any desired location. Such tapered boss and tapered sockets provide a means for adjusting the weight center of the counterbalance unit to a multiplicity of positions with respect to the crank arm. A bolt 16 is provided for holding the 55

crank arm and counterbalance unit in their respective adjusted positions. This bolt extends through the tapered boss 15 and through holes in the base of the tapered sockets 14.

5 In the lower part of the counterbalance unit, a plurality of bolt holes are provided as a means whereby supplemental weight elements 17 may be attached to or detached from the counterbalance unit as desired. These supplemental weight elements 10 may be attached to the counterbalance unit in any desired number by means of the bolts 18. A pitman of any preferred form may be attached to the crank arm 8 by means of the wrist pin 19 and a plurality of holes 20 15 are provided to permit adjustment of the wrist pin to different positions along the length of the crank arm 8.

Referring to the drawing, it will be apparent 20 that the counterbalance unit 5 may be easily attached to or detached from the crank arm 8. As shown in Figure 3, the tapered boss 15 is fitted in one of the tapered sockets 14 of the counterbalance unit and a bolt 16 is passed through the counterbalance unit and the crank to hold the tapered boss within the tapered socket in which 25 it is disposed.

To detach the counterbalance unit 5 from the crank 8, it is only necessary to remove the bolt 16 and then move the counterbalance unit along 30 the crank hub in a direction away from the crank arm 8 to such an extent that the tapered boss 15 will be disengaged from the tapered socket 14. In order that the counterbalance unit may be moved away from the crank 8 more easily, the 35 portion of the hub of the crank on which the counterbalance unit is suspended may be machined so as to taper slightly in a direction away from the crank.

In connection with the provision of a counterbalance weight structure which is movable along 40 the hub of the crank arm either toward or from the inner face of this crank arm, I have provided a pivoted latch 23 which is normally ineffective when the counterweight is connected to the crank arm. This latch may be swung downwardly 45 to embrace the upper part 12 of the counterweight structure and effectively maintain the counterbalance in spaced relation to the crank arm when desired so that the crank arm will be free to move in a rotary path without interference 50 from the counterbalance.

In order to provide a means whereby the counterbalance unit may be removed from the crank hub and the crank relieved of the weight 55 of the counterbalance unit and yet have the counterbalance unit in a position whereby it may be quickly and easily remounted on the crank hub, we have provided a bracket 20' or other supporting shelf immediately below the counterbalance unit. This bracket is intended 60 to receive and support the counterbalance unit when the nuts upon the bolts 21, which are made of extra length for this purpose, are sufficiently loosened to permit the counterbalance unit to be 65 practically entirely disconnected from the crank shaft. It will be understood that the counterbalancing unit may be attached either directly to the crank shaft or to the hub of the crank 8.

In either construction, the bolts 21 are of such 70 length that, after the bolt 16 has been removed to permit the removal of the tapered boss 15 from the tapered socket 14 in which it is disposed, the counterbalance attachment may be lowered to rest upon the bracket 20' to such an extent as to entirely relieve the crank shaft 9

or the crank hub of any weight of the counterbalance unit. At the same time, the counterbalance unit may be quickly and easily remounted on the crank-shaft 9 or the crank hub by the simple expedient of tightening the nuts on the bolts 21 to such an extent as to draw the counterbalance unit upwardly to its operative position.

5 By referring to the preceding description and the drawing attached hereto, it will be clearly 10 understood that we have provided a counterbalance unit which will permit any desired counterbalancing effect to be obtained. This desired counterbalancing effect may be obtained in several ways, the most simple of which would be by 15 adjusting the counterbalance unit and the crank laterally with relation to each other until the tapered boss 15 on the crank arm is in cooperative relation to the desired tapered socket 14 in the counterbalance unit. Another means of obtaining the desired counterbalancing effect is to vary the number of the supplemental weight elements 17 on the counterbalance unit. Still another means of obtaining the desired counterbalancing effect is by adjusting the pitman of 20 the drilling and pumping mechanism to various positions along the crank arm 8 by changing the position of the wrist pin 19 on the crank arm.

25 Also, by referring to the drawing, it will be apparent that our counterbalance unit, when 30 assembled, is located outside of the band wheel house 3 whereby it may be readily adjusted and operated, and not inside of the rig house where the counterbalance device would be more or less inaccessible due to lack of space. As shown, the 35 siding of the band wheel house 3 is between the front jack post 11 and the sprocket wheel 22 which provides a means for driving the sand reel 7. Furthermore, it will be seen that our device 40 is so constructed that the counterbalance unit 45 may be quickly and easily shifted in an arcuate path with relation to the crank arm, to synchronize the counterbalance effect with the load.

It will be seen that we have provided a counterbalance unit which may be drawn into rigid 45 relation to the crank. This is accomplished by means of the tapered boss and the complementally tapered sockets. The boss is large and, therefore, has a large shearing area which will permit the use of bolts for securing the crank 50 and counterbalance unit together and, at the same time, will ensure a rigidity of connection which cannot be economically obtained by the use of bolts alone.

It will also be apparent that by providing a 55 counterbalance unit which is so designed as to be attached to and operate with the crank of an oil well drilling and pumping mechanism, we have a means for counterbalancing such mechanism that has decided advantages over a band 60 wheel or walking beam counterbalance. One of these advantages resides in the fact that the crank may be assembled with the crank shaft in the factory. By assembling the crank and crank shaft in the factory, it is possible to do so 65 hydraulically or by attaching the crank to the crank shaft by a shrink fit, both of which operations are impractical in the field. With such assembly, a much more rigid fit between the crank and crank shaft may be obtained.

70 Another advantage resides in the fact that the wear and tear on the band wheel and the torsional stress on the crank shaft, such as produced by ordinary types of band wheel and walking beam counterbalances, are eliminated. To 75

visualize the strain to which the various parts of the apparatus are put, it is well to appreciate that in order to obtain a proper counterbalancing effect in oil well drilling and pumping mechanism, it is usually necessary to provide a weight of approximately four tons, the center of gravity of which is ordinarily 5 feet from the center of the crank shaft. In our device, we have connected the weight directly to the crank shaft 5 or the hub of the crank arm, which eliminates practically all of those stresses on the band wheel, keys, crank shaft and associated parts which arise when the counterbalance weight is attached to the band wheel. Furthermore, our 10 device has the additional advantage of being removable to such an extent that the crank shaft may be relieved of all weight of the counterbalance and yet the counterbalance unit will be in such position that it may be quickly and easily 15 remounted on the crank shaft or hub of the crank arm.

Still another advantage of our invention resides in the fact that only a relatively short time is required to attach and detach the counterweight to or from the crank shaft or crank hub and, consequently, to or from a position of effectiveness. This is an important advantage because it is well known that, when a pump ceases to operate in a well, water has a tendency to encroach on the well or, pumping in adjacent wells, acts to pull the oil away from the well which is not being pumped. Therefore, to cease pumping a well for other than a very short period of time will result in a considerable amount of pumping being necessary before the well will be returned to the condition it was in prior to the time that the pumping ceased.

A further advantage resides in the fact that our design and construction is such that the counterbalance weight is at a maximum distance from the center of the crank shaft. Obviously, the further the counterbalance weight is removed from the crank shaft the less weight is required. Therefore, our device will permit a relatively 40 small counterbalance weight to be used to obtain a relatively large counterbalancing effect.

Having thus described our invention, what we claim is:

1. In a well-pumping mechanism, a crank shaft, a supporting member for said crank shaft, a crank arm keyed on the outer end of said crank shaft and disposed at a location spaced from said supporting member, said crank arm having a hub formed as an integral part thereof which embraces said crank shaft, a counterbalance weight structure, means for suspending said counterbalance weight structure in juxtaposition to said crank arm and between said arm and said crank shaft supporting member, said means comprising a member adapted to embrace the hub of said crank arm, a plurality of bolts having their upper ends passing through sockets in said hub-embracing member, the lower ends of said bolts being connected to the body portion of said counterbalance weight structure, means for feeding said bolts into and out of said sockets to raise said counterbalance weight structure to a position in cooperative relation to said crank arm or to lower it into an inoperative position relative to said crank arm, said counterbalance weight suspending means being adjustable axially of said hub member, a shelf structure on said supporting member, said shelf structure being so located on said supporting member and the said bolts being of such length that when the counterbalance weight structure is adjusted into inoperative position it will rest on said shelf structure, and means other than said counterbalance weight suspending means for attaching said counterbalance weight directly to said crank arm when the weight and arm are in cooperative relation, said last-named means comprising a hole in said crank arm and a plurality of circumferentially spaced holes in said counterbalance weight structure any one of which may be brought into coincidence with said hole in said crank arm and a member passing into the corresponding holes in said crank arm and said weight structure. 10
2. In a well-pumping mechanism, a crank shaft, a supporting member for said crank shaft, a crank arm mounted on said crank shaft and disposed at a location spaced from said supporting member, said crank arm having a hub thereon which embraces said crank shaft, a counterbalance weight structure means for suspending said counterbalance weight structure in juxtaposition to said crank arm and between said arm and said crank shaft supporting member, said means comprising a member adapted to embrace the hub of said crank arm, a plurality of rods having their upper ends passing through sockets in said hub-embracing member, the lower ends of said rods being connected to the body portion of said counterbalance weight structure, means for feeding said rods into and out of said sockets to raise said counterbalance weight structure to a position in cooperative relation to said crank arm, or to lower it into an inoperative position relative to said crank arm where the crank shaft will be relieved of the weight of said counterbalance weight, and means other than said counterbalance weight suspending means for attaching said counterbalance weight directly to said crank arm when the weight and arm are in cooperative relation at any of a plurality of circumferential positions relative to said crank arm. 20
3. In a well-pumping mechanism, a crank shaft, a supporting member for said crank shaft, a crank arm mounted on said crank shaft, said crank arm having a hub which embraces said crank shaft, a counterbalance weight structure, means for suspending said counterbalance weight structure in juxtaposition to said crank arm, said means comprising a member adapted to embrace the hub of said crank arm, a plurality of rods having their upper ends passing through sockets in said hub-embracing member, the lower ends of said rods being connected to the body portion of said counterbalance weight structure, means for feeding said rods into and out of said sockets to raise said counterbalance weight structure to a position in cooperative relation to said crank arm or to lower it into an inoperative position relative to said crank arm where the crank shaft will be relieved of the weight of said counterbalance weight, and means other than said counterbalance weight suspending means for attaching said counterbalance weight directly to said crank arm when the weight and arm are in cooperative relation at any of a plurality of circumferential positions relative to said crank arm. 25
4. In a well-pumping mechanism, a crank shaft, a supporting member for said crank shaft, a crank arm mounted on said crank shaft, said crank arm having a hub which embraces said crank shaft, a counterbalance weight structure, means for suspending said counterbalance weight structure in juxtaposition to said crank arm, 30

said means comprising a member adapted to embrace the hub of said crank arm, a plurality of rods having their upper ends passing through sockets in said hub-embracing member, the lower ends of said rods being connected to the body portion of said counterbalance weight structure, means for feeding said rods into and out of said sockets to raise said counterbalance weight structure to a position in cooperative relation to said 5 crank arm or to lower it into an inoperative position relative to said crank arm where the crank shaft will be relieved of the weight of said counterbalance weight, and means other than said counterbalance weight suspending means 10 for attaching said counterbalance weight directly to said crank arm when the weight and arm are in cooperative relation.

5. In a well-pumping mechanism, a crank shaft, a crank arm mounted on said crank shaft, 20 said crank arm having a hub which embraces said crank shaft, a counterbalance weight structure means for suspending said counterbalance weight structure in juxtaposition to said crank arm, said means comprising a member adapted 25 to embrace the hub of said crank arm, a plurality of rods having their upper ends passing through sockets in said hub-embracing member, the lower ends of said rods being connected to the body portion of said counterbalance weight 30 structure, means for feeding said rods into and out of said sockets to raise said counterbalance weight structure to a position in cooperative relation to said crank arm or to lower it into an inoperative position relative to said crank arm 35 where the crank shaft will be relieved of the weight of said counterbalance weight.

6. In a well-pumping mechanism, a crank shaft, a crank arm mounted on said crank shaft, 40 said crank arm having a hub which embraces said crank shaft, a counterbalance weight structure, means for suspending said counterbalance weight structure in juxtaposition to said crank arm, said means comprising a member adapted 45 to embrace the hub of said crank arm, a plurality of rods having their upper ends passing through sockets in said hub-embracing member, the lower ends of said rods being connected to the body portion of said counterbalance weight 50 structure, means for feeding said rods into and out of said sockets to raise said counterbalance weight structure to a position in cooperative relation to said crank arm or to lower it into an inoperative position relative to said crank arm, said counterbalance weight suspending means 55 being adjustable longitudinally of said crank shaft, and means other than said weight suspending means for connecting said weight directly to said crank arm when said crank arm and said weight are in cooperative relation.

60 7. In a well-pumping mechanism, a crank shaft, a crank arm mounted on said crank shaft, a counterbalance weight structure, means for suspending said counterbalance weight structure in juxtaposition to said crank arm, said means 65 comprising a member supported by said crank shaft, a plurality of rods having their upper ends passing through sockets in said member, the

lower ends of said rods being connected to the body portion of said counterbalance weight structure, means for feeding said rods into and out of said sockets to raise said counterbalance weight structure to a position in cooperative relation to said crank arm or to lower it into an inoperative position relative to said crank arm, and means other than said weight suspending means for connecting said weight directly so said 5 crank arm when said crank arm and said weight are in cooperative relation, said means comprising a member extending from said crank arm and which fits into any of a plurality of spaced sockets in said counterbalance weight structure. 10

8. In a well-pumping mechanism, a crank 15 shaft, a crank arm mounted on said crank shaft, a counterbalance weight structure, means for suspending said counterbalance weight structure from said crank shaft and in juxtaposition to said crank arm, said suspending means being 20 adjustable to raise said counterbalance weight structure to a position in cooperative relation to said crank arm or to lower it into an inoperative position relative to said crank arm onto a support so that said crank shaft will be entirely relieved 25 of the weight of said weight structure, and means other than said weight suspending means for attaching said weight structure directly to said crank arm when said crank arm and said weight are in cooperative relation, at any of a plurality 30 of circumferential positions relative to said crank arm.

9. In a well-pumping mechanism, a crank 35 shaft, a crank arm mounted on said crank shaft, a counterbalance weight structure, means for suspending said counterbalance weight structure from said crank shaft, and in juxtaposition to said crank arm, said suspending means being adjustable to raise said counterbalance weight 40 structure to a position in cooperative relation to said crank arm or to lower it into an inoperative position relative to said crank arm onto a support so that said crank shaft will be entirely relieved 45 of the weight of said weight structure, and means other than said weight suspending means for attaching said weight structure directly to said crank arm when said crank arm and said weight are in cooperative relation at any of a plurality 50 of circumferential positions relative to said crank arm.

10. In a well-pumping mechanism, a crank 55 shaft, a crank arm mounted on said crank shaft, a counterbalance weight structure, means for suspending said counterbalance weight structure from said crank shaft and in juxtaposition to said crank arm, said suspending means being adjustable to raise said counterbalance weight structure or to lower it relative to said crank arm, and means other than said weight suspending means for attaching said weight structure directly 60 to said crank arm when said crank arm and said weight are in proper relation to each other at any of a plurality of circumferential positions relative to said crank arm.
